UNITED STATES PATENT OFFICE.

ALBERT H. DE VOE, OF ELIZABETH, NEW JERSEY, ASSIGNOR TO THE SINGER MANUFACTURING COMPANY, A CORPORATION OF NEW JERSEY.

SEWING-MACHINE FOR PRODUCING SCALLOPED TUCKS.

No. 858,161.

Specification of Letters Patent.

Patented June 25, 1907.

Application filed November 24, 1905. Serial No. 288,838.

To all whom it may concern:

Be it known that I, ALBERT H. DE VOE, a citizen of the United States, residing at Elizabeth, in the county of Union and State of New Jersey, have invented certain new and useful Improvements in Sewing-Machines for Producing Scalloped Tucks, of which the following is a specification, reference being had therein to the accompanying drawings.

- 10 This invention relates to an improvement in that class of sewing machines designed and fitted for producing scalloped edges of a form commercially known as "shell tucking"; and it has for its primary object to insure greater uniformity of action than has been practicable heretofore in such class of machines, and to provide a simple and effective construction and arrangement of parts coöperating to produce the described result.
- 20 The invention, in its preferred embodiment, consists in a sewing machine having any usual or suitable stitch-forming devices and a presser-foot coöperating with the feeding member for holding and advancing the work in the production of a straight-ahead seam along its edge, combined with a periodically-acting pusher movable transversely of the line of feed for indenting the edge of the fabric at intervals for the passage of the needle beyond the same, and a periodically-acting bifurcated auxiliary clamp-member for securely holding the edge of the work during the action of the pusher upon a portion intermediate those so held. The action of the feeding mechanism is preferably interrupted during the production of one or more stitches at the time the pusher is in active operation, and in the present embodiment, the fulcrum of the feed lever is dropped at intervals so
- 30 that the lifting cam has an insufficient throw to lift the feed-dog into engagement with the work at such times. It will thus be observed that the feeding-mechanism and the pusher and coöperating work-clamp act upon the work alternately in successive stitch-forming cycles in the production of a group of stitches; the stitch or stitches produced while the edge of the material is indented by the pusher being formed without the usual
- 40 advance of the work under the action of the feeding-mechanism in the latter part of one stitch-forming cycle preparatory to the succeeding stitch-forming operation of a series of stitch-forming cycles for producing a suc-

cession or group of stitches which the machine is designed to repeat in fixed order. In order that a shell-like scallop with convex upper side shall be invariably formed by the action of the pusher in conjunction with the stitch-forming devices, the throat-plate and presser-foot are formed with slightly inclined adjacent faces to present the edge of the work with a corresponding inclination to the operative end of the pusher, which reciprocates in a transverse channel formed in the throat-plate and is formed with a notch in its lower portion to receive the edge of the work and prevent its upward deflection by engagement of the pusher.

The invention will be understood by reference to the annexed drawings, in which

Figure 1 is a plan of a sewing machine embodying the present improvement, with the horizontal portion of the bracket-arm and the work-plate removed to expose the parts beneath, and Fig. 2 is a side elevation of the same, showing the stitch-forming mechanism. Fig. 3 is a front end view of the machine with the bracket-arm omitted and the parts below the same represented in their respective positions. Figs. 4 to 9 inclusive, are detail views representing the auxiliary clamping device and its actuating mechanism, Figs. 4 and 5 being detail views, taken from the side opposite that represented in Fig. 2, Fig. 6 being a detail elevational view taken at right angles to the preceding figures of certain of the parts represented therein, and Figs. 7, 8 and 9 being, respectively, perspective views of the auxiliary clamping member, the endwise movable shaft and crank-arm carrying the same and provided with the pusher, and the tilting member for the clamping jaws. Fig. 10 is a partial plan view of the machine with a pair of tucking guides, and representing the work under the stitching and scalloping operation. Fig. 11 is a detail plan view of the pusher and auxiliary clamp with their actuating mechanism. Fig. 12 is a plan of the throat-plate, and Fig. 13 a perspective view and Fig. 14 a bottom view of the presser-foot. Fig. 15 is a partial transverse sectional view of the throat-plate and presser-foot in their operative relations.

The sewing machine to which the present improvement is shown applied is of the well-known "Singer" single-chain-stitch type,

with base 1 from which rises the usual bracket-arm 2 which is in practice provided with the needle-bar 3 carrying the eye-pointed needle 4 which coöperates with the rotary looper 5 carried by the forward end of the main shaft 6 provided at its rearward end with the grooved belt-wheel 7 and balance-wheel 8.

The presser-bar 9 mounted, as usual, in the head of the bracket-arm 2 carries the presser-foot 10 normally pressed upon the throat-plate 11, set into the usual work-plate 11^x, for holding the material intermediate the feeding actions, and coöperating during the latter with the feed-dog 12 carried by the feed-bar 13 pivoted at 14 to the feed-rocker 15 and at 16 with the feed-lifting bar 17 pivotally connected at its forward end with the depending portion of an eccentric strap 18 embracing the usual lifting eccentric upon the main shaft 6 and at its opposite end fulcrumed by means of a pin 19^x upon the upper end of the upright link 19 whose lower end is pivoted to the adjacent end of a lever 20 fulcrumed at 21 upon the fixed bearing block 22 and having at its opposite end a pin or roller-stud 23 entering a cam-groove 24 in the rotary cam 25 to be later described.

The feed-rocker 15 is mounted upon the center screws 26 and provided with the usual depending crank-arm 27 to which is pivoted one end of an actuating lever 28 provided with a yoke 29 intermediate its ends embracing the usual feed-actuating eccentric upon the main shaft 6, and having its opposite end provided with a lateral stud entering a guiding groove in the head of the feed-regulating lever 30 pivoted upon the machine frame by a suitable fulcrum screw and provided with a finger piece 32 for shifting the same to vary the inclination of its guiding groove for correspondingly varying the effective action of the feed-actuating cam upon the feed-rocker 15, in a manner well-known.

The feed-rocker actuating mechanism above described is that of the well-known Singer No. 24 chain-stitch machine in which the general form and arrangement of the actuating bar is similar to that of the United States patent to Diehl No. 339,624, dated April 13, 1886, with the controlling link 18 of such patent replaced by a pivoted member having a controlling slide-way for the adjacent end of the actuating-bar, such as that represented in the patent to Diehl No. 388,345, dated Aug. 21, 1888.

The pusher 33 consists of a rigid finger having a vertical slot 34 in its forward or operative end to embrace the needle path and the transverse notch 35 in the lower edge at such end to receive the edge of the material which it operates upon, the rearward end of the pusher being secured to a bracket-piece 36 extending upwardly from the end 65 of a lateral arm 37 mounted upon one end

of an endwise-movable rod 38 provided at its opposite end with a rigid angular arm 39 carrying a roller stud 40 which enters a cam-groove 41 in the hub of the rotary cam-wheel 25 having peripheral gear-teeth 42 meshing with a pinion 43 fixed upon the main shaft 70. As herein represented, the intermeshing gear-wheels 42 and 43 are so proportioned that the member 25 makes one rotation to each five of the main shaft. As shown in the drawings, the work-plate 11^x is provided with a housing 11^y serving as a guard for the rotating cam-member 25. The cam-wheel 25 is provided upon the side opposite the grooved hub referred to with a tubular hub 44 mounted in the forked bearing 45 of the machine frame and provided with a fixed collar 46 intermediate the spaced portions of the supporting bearing to hold the same from endwise movement. The reciprocating rod 38 is fitted to the bore of and supported by the cam-wheel 25 and is prevented from rotation therewith by means of a steady-pin 47 carried by the angular arm 39 and entering a horizontal slot 48 in a standard 49 80 attached to the bed-plate.

The auxiliary work-clamp comprises a shank-portion 50 having at its forward end the spaced parallel clamping jaws 51 and at its rear end the perforated ears 52 embracing a perforated central lug 53 upon a tilting block 54 pivotally mounted by means of a common fulcrum screw 55 upon the fixed bearing bracket 56 secured upon the machine frame. The tilting block 54 is provided upon its forward end with an upright stud 57 passing through an aperture in the upper clamp-member 50 between which and a collar 58 upon said stud is interposed a spring 59 whereby the bottom of the shank 50 is maintained normally seated upon the corresponding end of the block 54. The rearward end of the block 54 is held yieldingly downward to maintain the jaws 51 elevated above the throat-plate by means of a spring 60 surrounding a fixed pin 61 projecting upwardly from the foot of the bearing bracket 56 through a suitable aperture 62 in the block 54, such spring being interposed between the top of the latter and an adjustable collar 63 upon the pin 61.

The tilting block 54 carries at its rearward end a screw-pin 64 whose lower operative end projects downwardly beneath the same and into the path of movement of a transverse cam-face 65 formed upon the outer end of a lever 66 pivotally mounted at the opposite end by means of a stud-screw 67 upon the arm 37 attached to the reciprocating rod 38 and movable sidewise therewith. The arm 37 is provided intermediate its ends with a transverse hole entered by the outer end portion of a fixed guide-pin 68 projecting from the machine frame, and of such length that when the arm 37 is shifted later- 130

ally and carries with it the lever 66, the transverse notch 69 therein is caused to embrace the outer end portion of the pin 68 which thus temporarily forms a support for the lever 66, which is initially raised into elevated operative position by engagement of its outer end portion having the cam-face 65 with the upper side of the eccentric strap 18 in opposition to a spring 70 interposed between the same and the bracket-piece 36 carrying the pusher 33.

The arm 37 is necessarily fixed rigidly upon its reciprocating supporting-rod 38, as it carries the pusher 33 which is necessarily held against vertical movement in the performance of its function, while the lever 66 has a pivotal connection with said rigid arm in order to rise and fall with the feed-lifting eccentric strap from which it derives its operative movements, although its period of operative relation with the work-clamp which it actuates is controlled by its resting upon the pin 68 from which it is disengaged only by the retractive movement of the rod 38 and supporting-arm 37 carried thereby.

The presser-foot 10 is provided with a long transverse needle slot 71 extending from its inner edge slightly beyond the needle-path and sufficiently wide to receive the pusher 33 in performing its normal function, and with similar slots 72 upon opposite sides thereof to receive the spaced jaws 51 of the auxiliary clamp 50, which latter is provided with a finger 74 projecting slightly above the presser-foot and adapted to engage the same when it is lifted for introduction or removal of the work to cause the clamp 50 to be similarly raised in opposition to the spring 59 for a similar purpose. The sole portion of the foot is provided with a recess 73 around the inner end of the needle-slot 71 to provide clearance for the fabric when puckered under the foot by the advancement of the pusher.

The upper face of the throat-plate 11 has a slightly raised portion at the left provided with the usual feed-dog slots 75, and such elevated portion terminates at the inner side (on the right in Fig. 12) and in the direction of the bracket-arm 2, in a slight bevel disposed parallel with the feed-slots and merging into a lower portion which is or may be flush with the work-plate 11* in a usual or well known manner. A pusher clearance groove 76, having its bottom at the same level as the flush portion of the throat-plate is formed in the elevated portion of the throat-plate, and has disposed therein the elongated needle-hole 77 arranged crosswise thereof and in line with the shorter feed-dog slot 75 in order to provide clearance to permit of the easy setting of the stitches. The pusher-clearance groove 76 is provided to insure that the bottom of the pusher shall be maintained below the lower face of the material, resting upon the raised portion of the throat-plate 11,

which will therefore be unable to get under the same and cause the clogging of the device and the marring of the work. As the rocking of the lever 20 under the action of the cam 24 causes the periodical shifting of the working position of the feeding member 12 sufficiently low to prevent operative engagement with the work, it is evident that the material is thus permitted to lie undisturbed upon the throat-plate during the stitch-forming cycle when the pusher and work-clamp are in operative engagement with the work, thus obviating any interference in the actions of the work-advancing and edge-indenting members of the machine, and insuring the proper engagement and control of the edge of the material by the notched operative end of the pusher 33.

While the present improvement is obviously adapted for other classes of work than that upon the folded edges of material to be stitched, it is represented in Fig. 10 of the accompanying drawings as provided with a tucking guide comprising a base-plate 78 adjustably secured upon the work-plate by means of screws 79 and provided with a guiding edge 80 for the edge of the fold to be scalloped and with a tuck-gaging blade 81 secured adjustably thereon by means of a clamp-screw 82 passing through a suitable slot 83 in the shank of the same. The fabric *a* is shown folded over the thin plate 84 which is or may constitute the hinged tucking blade of a well-known form of tucking device. The base-plate 78 of the tucking attachment is further represented as provided with a cord-guiding eye 85 through which a cord *b* is led to a point adjacent the finger 86 of the tucking blade 84, to be pressed against such edge by the pusher and bound thereto by the over-edge stitches *c* at the bases of the scallops.

The operation of the machine is as follows: The material having been folded over the tucking blade 84 and inserted under the gaging blade 81 and in contact with the guiding edge 80 of the base plate 78 while the presser-foot is raised, the latter is dropped upon the work and the machine set in motion. During the first four reciprocations of the needle 4, and corresponding rotations of the hook 5, the feed-dog 12 makes its usual feeding and lifting motions and operates in conjunction with the presser-foot 10 to advance the work after each such reciprocation of the needle, thereby producing three straight-ahead stitches at a distance from the edge of the fold. Just after the rise of the needle in its fourth reciprocation, the rod 38 is shifted forwardly under the action of the cam 41 upon the roller-stud 40 carried by the angular arm 39, the initial portion of which movement shifts the arm 37 forward carrying with it the pusher 33 and cam-lever 66, the inclined portion of whose cam-face comes in contact with the point of the screw-pin 64 of the tilting block 54, there-

by rocking it and consequently the clamp-lever 50 upon the common fulcrum-pin 55 and causing the jaws 51 to clamp the fabric firmly, though yieldingly, upon the elevated 5 portion of the throat-plate 11, while the pusher 33 continues to advance and thereby indent the edge of the material intermediate the jaws 51 to crowd the same inwardly beyond the needle-hole 77 and into the clearance recess 73 of the presser-foot, thereby permitting the needle to clear the edge of the goods in its succeeding descent. Meanwhile, the rock-lever 20 has been tilted by the entrance of its stud 23 into the portion of the 15 cam-groove 24 nearest the center of rotation to lower the fulcrum 19* of the feed-lifting bar 17, by which the working position of the feed-dog is sufficiently lowered to prevent its engagement, even at its then highest position, with the under side of the work and the feed-dog is thus robbed of its normal feeding action. While the initial lifting movement of the lever 66 was produced by means of the feed-lifting cam embraced by the 25 eccentric strap 18, such lever 66 would have been permitted to drop immediately under the continued rotation of the eccentric were it not that the lateral movement of such lever with its carrying member 37 caused the top 30 of its transverse groove 69 to come into engagement with the sustaining pin 68 by which its elevation is maintained while in operative position to insure the continued action of the clamping jaws 51 until the retraction 35 of the rod 38 under the action of the cam 25 causes the disengagement of the cam-lever from its supporting pin.

As represented in the drawings, the feed-controlling cam-groove 24 is so timed in the 40 cycle of operation of the machine that the feeding action is interrupted just prior to the action of the pusher in the production of the first overedge stitch, by which such stitch is caused to be laid from the preceding needle 45 puncture directly over the indented edge of the material at a right angle to the line of the previous stitches, while the resumption of feeding immediately after the formation of such initial overedge stitch causes the succeeding overedge stitch to be laid diagonally in respect of the first depth-stitch needle puncture of the succeeding series of straight-ahead stitches. It is, however, evident that 50 by suitable changes of the cam-grooves and disposition of their operative portions, all the overedge stitches may be made at right angles to the straight-ahead stitches and at any suitable equal or unequal intervals, while the omission of the feed-interrupting device or 55 the employment of a uniformly-acting feeding mechanism of well-known type would cause the production of diagonally-laid over-edge stitches only.

While the tucking attachment is herein 60 represented as provided with means for guid-

ing a cord along the scalloped edge of the fold, it is evident that the mere omission of the cord will enable the machine to produce an uncorded scalloped edge such as is demanded for certain classes of work.

The bevel of the throat-plate downwardly and away from the needle-path, and the corresponding inclination of the inner slotted edge of the presser-foot, as represented particularly in Figs. 12 to 15 inclusive, produces a like inclination of the margin of the material clamped between the same, whereby the action of the pusher upon the extreme edge of the material tends to bow the adjacent portion of the material upwardly and give the 80 edge a concave shape and highly ornamental appearance; especially as the relative directions in which the margin of the material extends and movement of the pusher are such as to insure the uniform action of the character described.

From the foregoing description it will be observed that the principal or characteristic features of the present improvement are the special clamping device for the material upon 90 opposite sides of the pusher, and designed to operate during the action of the latter upon the work, and the feed interrupting device for the production of overedge binding stitches at a right angle to the line of straight-ahead 95 stitches, and that their specific embodiment may be modified to a considerable extent without departure from the present invention.

Having thus set forth the nature of the invention, what I claim herein is,—

1. In a sewing machine, the combination with the stitch-forming and feeding mechanisms, of a pusher movable transversely of the direction of feed and adapted to engage the edge of the work undergoing the stitching operation, a work-clamp adapted to engage the work adjacent said pusher, and means acting during the production of one stitch for effecting the engagement of the work by said 100 pusher and work-clamp but inactive during the production of a succeeding stitch.

2. In a sewing machine, the combination with the stitch-forming mechanism, feeding mechanism and actuating means therefor 115 inoperative during a complete stitch-forming cycle in the production of a succession of stitches, of a pusher movable transversely of the direction of feed and adapted to engage the edge of the work undergoing the 120 stitching operation, a work-clamp adapted to engage the work adjacent said pusher, and means for actuating said pusher and work-clamp to engage the work during the period of inaction of the feeding mechanism.

3. In a sewing machine, the combination with the stitch-forming mechanism, feeding mechanism and actuating means therefor 125 inoperative during a complete stitch-forming cycle in the production of a succession of 130

stitches, of a pusher movable transversely of the direction of feed and adapted to engage the edge of the work undergoing the stitching operation, a work-clamp adapted to engage the work adjacent said pusher, means for actuating said pusher and work-clamp to engage the work during the period of inaction of the feeding mechanism, and means connected with the feeding mechanism whereby the pusher and work-clamp are disengaged from the work after operative engagement therewith.

4. In a sewing machine, the combination with the stitch-forming mechanism and feeding-mechanism comprising a reciprocating feed-bar and a lifting bar connected therewith and provided with means for lowering the working position of said feed-bar during a complete stitch-forming cycle and maintaining the same raised in operative position in a succeeding stitch-forming cycle, of a pusher movable transversely of the direction of feed and adapted to engage the edge of the work undergoing the stitching operation, a work-clamp adapted to engage the work adjacent said pusher, and means for actuating said pusher and work-clamp for engagement of the work during the stitch-forming cycle in which the feed-bar is lowered from working position.

5. In a sewing machine, the combination with the stitch-forming and feeding mechanisms, of a pusher movable transversely of the direction of feed and adapted to engage the edge of the work adjacent that portion undergoing the stitching operation, a work-clamp adapted to engage the work adjacent said pusher, and means active during a stitch-forming cycle and inactive during a plurality of subsequent complete stitch-forming cycles in the production of a succession of stitches in actuating said pusher and work-clamp to engage the work.

6. In a sewing machine, the combination with the stitch-forming and feeding mechanisms, of a pusher movable transversely of the direction of feed and adapted to engage the edge of the work adjacent that portion undergoing the stitching operation, a work-clamp adapted to engage the work adjacent said pusher, means for effecting and maintaining the operative engagement of said pusher and work-clamp with the work for a complete stitch-forming cycle or cycles and rendering and maintaining the same inoperative for a succeeding stitch-forming cycle in the production of a succession of stitches, and controlling means for the feeding-mechanism whereby its action upon the work is interrupted for the stitch-forming cycle or cycles while the pusher and work-clamp are in operative engagement with the work.

7. In a sewing machine, the combination with stitch-forming mechanism and feeding mechanism comprising a reciprocating feed-

bar and a lifting bar mounted upon a movable fulcrum at one end and provided at the other end with means for raising and lowering the same and having intermediate its ends a pivotal connection with said feed-bar, of a pusher movable transversely of the direction of feed and adapted to engage the edge of the work adjacent that portion undergoing the stitching operation, an intermittently-acting work-clamp mounted independently of said pusher but adapted to engage the work adjacent thereto, means for alternately moving said pusher and work-clamp respectively into and out of operative engagement with the work in the production of successive stitches, and means for lowering the fulcrum of the feed-lifting lever to change the working position of the feeding member while the pusher and work-clamp are in engagement with the work.

8. In a sewing machine, the combination with stitch-forming mechanism and feeding mechanism comprising a reciprocating feed-bar and a lifting bar pivotally connected intermediate its ends with said feed-bar, a rotary main shaft from which the operative movements of the stitch-forming and feeding mechanisms are derived, a rotary cam-wheel geared to and adapted to rotate at a slower speed than said main shaft, and a shift lever pivotally mounted upon a fixed bearing intermediate its ends and carrying at one end a fulcrum for said lifting bar and engaging at the other end said cam-wheel, of a pusher movable transversely of the direction of feed and adapted to engage the edge of the work adjacent that portion undergoing the stitching operation, an intermittently-acting work-clamp mounted independently of said pusher but adapted to engage the work adjacent thereto, and means for alternately moving said pusher and work-clamp respectively into and out of operative engagement with the work in the production of successive stitches while the fulcrum-carrying end of said shift lever is in its lowered position under the action of said cam-wheel.

9. In a sewing machine, the combination with stitching-forming and feeding mechanisms, of a pusher movable transversely of the direction of feed and adapted to engage the edge of the work adjacent that portion undergoing the stitching operation, actuating means for alternately moving said pusher respectively into and out of operative engagement with the work in the production of successive stitches, an intermittently-acting work-clamp mounted independently of said pusher but adapted to engage the work adjacent thereto, actuating means for said work-clamp, and means acting in conjunction therewith for controlling the duration of the operative relation of said work-clamp with the work.

10. In a sewing machine, the combination

- with stitch-forming and feeding mechanisms, and means for actuating the same, of a pusher movable transversely of the direction of feed and adapted to engage the edge of the work adjacent that portion undergoing the stitching operation, actuating means for alternately moving said pusher respectively into and out of operative engagement with the work in the production of successive stitches, an intermittently-acting work-clamp mounted independently of said pusher but adapted to engage the work adjacent thereto, actuating means for said work-clamp deriving its movements from the feed-actuating means, and means acting in conjunction therewith for controlling the duration of the operative relation of said work-clamp with the work.
11. In a sewing machine, the combination with stitch-forming and feeding mechanisms, and means for actuating the same, of a pusher movable transversely of the direction of feed and adapted to engage the edge of the work adjacent that portion undergoing the stitching operation, actuating means for moving said pusher into operative engagement with the work during one stitch-forming cycle and out of such operative engagement for a succeeding stitch-forming cycle, a work-clamp adapted to engage the work adjacent said pusher, actuating means including a positively moving element for producing an initial clamping action of said work-clamp, and a holding device operative in conjunction with the actuating means for the work-clamp but independent of said positively moving element whereby the engagement of the work-clamp with the work may be maintained after its initial actuation.
12. In a sewing machine, the combination with stitch-forming and feeding mechanisms, and means for actuating the same, of a pusher movable transversely of the direction of feed and adapted to engage the edge of the work adjacent that portion undergoing the stitching operation, actuating means for moving said pusher into operative engagement with the work during one stitch-forming cycle and out of such operative engagement for a succeeding stitch-forming cycle, a work-clamp adapted to engage the work adjacent said pusher, actuating means for producing an initial clamping action of said work-clamp, and including a member carried by and movable in respect of the pusher-actuating means for controlling the duration of the operative relation of said work-clamp and its actuating means, and a holding device independent of the work-clamp actuating means and acting upon said member whereby the engagement of the latter with the work may be maintained after its initial actuation, and subsequently interrupted upon the retraction of the pusher-actuating means operating to carry said member out of engagement with said holding device.
13. In a sewing machine, the combination with stitch-forming and feeding mechanisms, and means for actuating the same, of a pusher movable transversely of the direction of feed and adapted to engage the edge of the work adjacent that portion undergoing the stitching operation, a reciprocating carrier for said pusher, a pivoted work-clamping lever mounted upon a fixed fulcrum and adapted to engage the work adjacent said pusher; a clamp-actuating member mounted upon the pusher carrier and adapted to be carried thereby into operative relation with said work-clamping lever, and means independent of said pusher-carrier for actuating said member.
14. In a sewing machine, the combination with stitch-forming and feeding mechanisms, of a pusher movable transversely of the direction of feed and adapted to engage the edge of the work adjacent that portion undergoing the stitching operation, an intermittently-acting work-clamping lever mounted independently of said pusher but adapted to engage the work adjacent thereto, means for alternately-moving said pusher respectively into and out of operative engagement with the work in the production of successive stitches, actuating means for moving said clamping lever into engagement with the work substantially simultaneously with the pusher, and a yielding connection between said clamping lever and its actuating means.
15. In a sewing machine, the combination with stitch-forming and feeding mechanisms, of a pusher movable transversely of the direction of feed and adapted to engage the edge of the work adjacent that portion undergoing the stitching operation, an intermittently-acting work-clamping lever adapted to engage the work adjacent said pusher, a fixed bearing block carrying a fulcrum-pin upon which said clamping lever is mounted, a tilting block also mounted upon said fulcrum-pin, a yielding connection between said tilting block and said clamping lever, and means adapted to engage said tilting block for moving the clamping lever yielding upon the work while said pusher is in engagement therewith.
16. In a sewing machine, the combination with stitch-forming and feeding mechanisms, a throat-plate and a presser-foot provided with a plurality of transverse slots extending inwardly from one edge thereof, of a pusher movable transversely of the direction of feed and adapted to enter one of said transverse slots in the presser-foot to engage the edge of the work adjacent that portion undergoing the stitching operation, an intermittently-acting work-clamp mounted independently of said pusher and provided with a pair of work-engaging jaws adapted to enter transverse slots in said presser-foot upon opposite sides of the pusher for engagement with the work and with a projecting finger extending

- above said presser-foot, actuating means for alternately moving said pusher and work-clamp respectively into and out of operative engagement with the work in the production of successive stitches, and a yielding connection between said work-clamp and its actuating means.
17. In a sewing machine, the combination with stitch-forming and feeding mechanisms, of a pusher movable transversely of the direction of feed and adapted to engage the edge of the work adjacent that portion undergoing the stitching operation, actuating means for alternately moving said pusher respectively into and out of operative engagement with the work in the production of successive stitches, and means whereby the action of the feeding mechanism may be interrupted throughout a complete stitch-forming cycle during the engagement of said pusher with the work.
18. In a sewing machine, the combination with stitch-forming and feeding mechanisms, of a pusher movable transversely of the direction of feed and adapted to engage the edge of the work adjacent that portion undergoing the stitching operation, actuating means for alternately moving said pusher respectively into and out of operative engagement with the work in the production of successive stitches, and means connected with the pusher-actuating means whereby the action of the feeding mechanism may be interrupted throughout a complete stitch-forming cycle during the engagement of said pusher with the work.
19. In a sewing machine, the combination with stitch-forming mechanism comprising a reciprocating needle and complementary stitch-forming devices, and feeding mechanism, of a pusher movable transversely of the direction of feed and adapted to engage the edge of the work adjacent that portion undergoing the stitching operation, means for alternately moving said pusher respectively into and out of operative engagement with the work in the production of successive stitches, a throat-plate provided with a needle aperture and a transverse pusher-clearance channel extending across the same to receive the lower edge of said pusher, and a presser-foot for holding the work upon said throat-plate.
20. In a sewing machine, the combination with stitch-forming mechanism comprising a reciprocating needle and complementary stitch-forming devices, and feeding mechanism, of a pusher movable transversely of the direction of feed and adapted to engage the edge of the work adjacent that portion undergoing the stitching operation, means for alternately moving said pusher respectively into and out of operative engagement with the work in the production of successive stitches, a throat-plate provided with a needle aperture and a transverse pusher-clearance channel extending across the same to receive the lower edge of said pusher, and a presser-foot having a transverse needle-slot with clearance recess in its lower face around the inner end of said slot and adjacent the needle-path.
21. In a sewing machine, the combination with stitch-forming mechanism comprising a reciprocating needle and complementary stitch-forming devices, and feeding mechanism, of a pusher movable transversely of the direction of feed and adapted to engage the edge of the work adjacent that portion undergoing the stitching operation, means for alternately moving said pusher respectively into and out of operative engagement with the work in the production of successive stitches, a throat-plate provided with a needle aperture and with an elevated portion embracing the same and a laterally-depressed portion connected therewith by a beveled portion and having a transverse pusher-clearance channel extending across said needle-hole, and a presser-foot for holding the work upon said throat-plate and having its lower or operative face shaped to fit the top of said throat-plate.
22. In a sewing machine, the combination with stitch-forming mechanism comprising a reciprocating needle and complementary stitch-forming devices, and feeding mechanism, of a pusher having a nose which is forked to embrace said needle and undercut in the work-engaging extremity, said pusher being movable transversely of the direction of feed and adapted to engage the edge of the work adjacent that portion undergoing the stitching operation, means for alternately moving said pusher respectively into and out of operative engagement with the work in the production of successive stitches, a throat-plate provided with a needle aperture and a transverse pusher-clearance channel extending across the same to receive the lower edge of said pusher, and a presser-foot for holding the work upon said throat-plate.
23. In a sewing machine, the combination with the stitch-forming and feeding mechanisms, of a pusher movable transversely of the direction of feed and adapted to engage the edge of the work adjacent that portion undergoing the stitching operation, a tuck-folding blade disposed in advance of the line of movement of said pusher and adapted to present a folded edge of fabric thereto, cord-guiding means for laying a cord along the edge of said fold and in the path of movement of said pusher, and means for alternately moving said pusher respectively into and out of operative engagement with said folded edge of fabric in the production of successive stitches.

24. In a sewing machine, the combination with stitch-forming and feeding mechanisms, of a pusher movable transversely of the direction of feed and adapted to engage the edge 5 of the work undergoing the stitching operation, means for actuating said pusher for engagement with the work for a stitch-forming cycle and remaining inactive thereafter during a plurality of stitch-forming cycles, and 10 means for actuating the stitch-forming mechanism to produce stitches both during and intermediate the periodical engagements of the pusher with the work.

25. In a sewing machine, the combination 15 with stitch-forming mechanism and a feeding member, of a pusher movable transversely of the direction of feed and adapted to engage the edge of the work undergoing the stitching operation, means for actuating said pusher 20 for engagement with the work, actuating means for imparting an operative movement to said feeding member for each stitch-forming cycle, and means whereby the working position of said feeding member is automatically shifted to prevent engagement with 25 the work throughout a complete stitch-form-

ing cycle in which the pusher engages the work.

26. In a sewing machine, the combination with stitch-forming mechanism and a feeding member, of a pusher movable transversely of the direction of feed and adapted to engage the edge of the work undergoing the stitching operation, a work-clamp adapted to engage the work adjacent said pusher, means for 30 periodically actuating said pusher and work-clamp for engagement with the work, actuating means for imparting an operative movement to said feeding member for each stitch-forming cycle, and means whereby the working 35 position of said feeding member is automatically shifted to prevent engagement with the work throughout a complete stitch-forming cycle in which the pusher and work-clamp engage the work.

In testimony whereof, I have signed my name to this specification, in the presence of two subscribing witnesses.

ALBERT H. DE VOE.
